TONGS

George S. Peters, Evanston, Ill.

Application April 2, 1942, Serial No. 437,313

7 Claims. (Cl. 294—11)

This invention relates to tongs and particularly to clinker tongs for removing clinkers from the fire bed of stoker-fired coal-burning domestic furnaces and the like.

Clinker tongs as heretofore constructed have been difficult to handle and manipulate in the required clinker loosening and clinker removing operations, and in addition, prior clinker tongs have in most instances tended to pierce and split the clinker in the course of the grasping and removing operation. In view of the foregoing it is an important object of the present invention to enable clinkers to be removed quickly and easily from the fire bed of a domestic furnace or the like, and a further object is to avoid or substantially eliminate undesired piercing, breaking or splitting of clinkers in the course of the clinker removing operations.

Further objects related to the foregoing are to reduce the effort required in removing clinkers from the fire bed of a domestic furnace or the like; to enable clinker tongs to be used easily and conveniently for loosening clinkers from the balance of the fire bed; and to provide for efficient and convenient application of the operating and manipulating forces to the clinker tongs during the clinker loosening and clinker removing operations.

In clinker tongs as heretofore used it has been necessary to apply substantial clamping forces to be understood that these are capable of or in other words, from the time when the clinker is lifted from the fire bed until the clinker is dropped into the usual ash receiver. The necessity for the application of a continuous clamping force to the clinker has rendered the clinker removing operation unduly tiresome, and has also tended to cause splitting of the clinkers in the course of the removing operation. In view of the foregoing, another object of this invention is to enable the clinker tongs to support the clinker freely with a shovel-like action and without the application of objectionable gripping or crushing forces thereto during the major portion of the clinker removing operation, and particularly it is an object to enable the clinker tongs to so support a clinker after the clinker has been lifted from the fire bed and while it is being moved out of the fire box.

Other and further objects of the present invention will be apparent from the following description and claims and will be understood by reference to the accompanying drawing which, by way of illustration, show a preferred embodiment and the principle thereof and what I now

consider to be the best mode in which I have contemplated applying that principle. Other embodiments of the invention employing the same or equivalent principle may be used and structural changes may be made as desired by those skilled in the art without departing from the present invention and the purview of the appended claims.

In the drawing:

Fig. 1 is a perspective view of a clinker tongs embodying the features of the invention, the parts being shown in the relation in which they are positioned during a clinker loosening operation;

Fig. 2 is a perspective view showing the clamping means of the tongs in position to be moved into clamping relation to a clinker;

Fig. 3 is a perspective view showing the tongs after a clinker has been clamped thereby;

Fig. 4 is a perspective view showing the tongs after the clinker has been manipulated to position on the tongs for removal from the furnace;

Fig. 5 is a perspective view illustrating the manner of discharge of a clinker from the tongs; and

Fig. 6 is a plan view taken along the line 6—6 and showing the manner in which the clinker is clamped in the tongs, and the manner in which it is freely supported during removal from the furnace.

In the form chosen for disclosure herein the invention is embodied in a clinker tongs having an elongated body member or handle shaft 10 adapted to be grasped adjacent to one end by the user to manipulate relatively movable clinker engaging elements which are disposed at the other end of the shaft, and these clinker engaging elements are so formed and related to each other and to the handle shaft 10 as to be adapted to cooperate as a clinker engaging means at certain times in the use of the device, while at other times in a clinker removing operation certain of these clinker engaging elements may be utilized to loosen the clinker and separate the same from the fire bed, and in addition, certain of the clinker engaging elements are so constituted and arranged that clamping pressure upon the clinker is required for but a short period, after which at least certain portions of these last mentioned clinker engaging elements may serve to freely support the clinker with a cradling or shovel-like action and without the application of clamping or piercing forces thereto such as might tend to break the clinker and cause it to be dropped from the tongs.

The handle shaft 10 preferably comprises two

elongated members which may be grasped by the user at spaced points near one end thereof to manipulate the tongs as a whole as well as to manipulate the clinker engaging elements carried by the other ends of these members. Thus the handle shaft 10, as herein shown, comprises an elongated round rod 11 surrounded by an elongated tubular member or sleeve 12, and the two members 11 and 12 are so related that the sleeve 12 may be rotated about the axis of the rod 11, or may be shifted longitudinally of the rod. At one of its ends the rod 11 is bent to an elongated loop formation which affords a handle 13 projecting radially with respect to the axis of the rod 11. In the use of the clinker tongs this handle 13 is grasped by one hand of the user, while the other hand of the user grasps an enlarged sleeve-like handle 14 made from wood or like material and secured on the sleeve 12 in spaced relation to the handle 13.

The clinker engaging elements of the present clinker tongs are mounted on the other ends of the elongated members 11 and 12 for manipulation thereby, and as herein shown the rod 11 has a pair of diverging tines 15 thereon against which a clinker C may be clamped by a clamping member 16 mounted on the sleeve 12 and manipulated and clamped by movement of the sleeve 12 relative to the rod 11. The tines 15, in accordance with the present invention, are so formed and arranged with relation to each other and with relation to the handle shaft 10 and the clamping member 16 that the tines 15 may serve a variety of functions which materially simplify the removal of clinkers from the fire bed and from the furnace. Thus the tines 15 are secured at 17 to the end of the rod 11, as by welding, and from this juncture the tines 15 preferably extend in diverging directions from the axis of the rod 11, as indicated at 18 in Fig. 6, to thereby attain an initial spacing of the tines at the base portions 18 thereof.

The tines 15 are then extended from the base portions 18 thereof so as to diverge symmetrically throughout their intermediate portions 19, and the diverging portions 19 may be located in a plane which includes the axis of the rod 11, or may be located, as in the present form, in a plane which is at a slight angle to the axis of the rod 11. The diverging intermediate portion 19 of the tines 15 are of substantial length, and merge with curved portions 20 of the tines, and these curved portions are substantially similar and terminate in end portions 21 located at substantially right angles to the axis of the rod 11 and projecting away from such axis. The extreme ends of the end portions 21 of the tines 15 are sharpened to some extent as indicated at 21' in Fig. 1, and hence the end portions 21 may be conveniently and easily forced into the fire bed to loosen the clinker C for removal from the fire bed.

The clamping member 16 is preferably arranged to provide a broad and relatively large area surface for clamping engagement with the clinker, thereby to avoid piercing or splitting of the clinker, and to this end the clamping member 16 comprises a rod 23 secured at one end as by a welded joint 24 to the sleeve 12 and having a cross bar 25 secured as by welding upon its other end. The rod 23 is bent so as to extend outwardly from the sleeve 12, and is then bent so as to extend substantially parallel to the sleeve 12 and generally toward the tines 15. The clamping member 16 is thereby made of a generally

T-shaped form, and the cross member 25 is so disposed that when the clamping member 16 is located in the position shown in Figs. 2 and 3, the cross member 25 moves toward the adjacent side faces of the end portions 21 of the tines 15. The relation of the cross member 25 to the sleeve 12 is such that in a clamping movement from the released position shown in Fig. 2 to the clamped position of Fig. 3, the cross member 25 may be located substantially perpendicular to the end portions 21 of the tines 15.

The cross member 25 is so formed and constructed that a clamping operation thereof will not ordinarily tend to stress a clinker with a beam-like action between the two end portions 21 of the tines, and the cross member 25 is therefore made of a length which is substantially equal to distance between the end portions 21 of the tines, as will be evident in Fig. 6 of the drawing. Thus the clamping member 16 has a broad bearing area which, through longitudinal shifting movement of the sleeve 12 with respect to the rod 11, may be brought to bear on side of a clinker C, and by such clamping action the clamping member 16 presses the other side of the clinker against the side faces of the end portions 21 of the tines 15. Such clamping is accomplished without application of breaking or bending forces to the clinker and without the use of sharp engaging surfaces or points which might tend to pierce or split the clinker.

The construction and arrangement of the clinker tongs as thus described enables a user to loosen a clinker from the fire bed and to remove the same from the furnace with unusual ease and convenience, for the present clinker tongs may be manipulated to loosen the clinker and to clamp the clinker and position the same on the shovel-like support afforded by the spaced tines 15, as shown in Fig. 4, after which the user may readily withdraw the clinker from the furnace with the clinker supported freely upon the tines 15. Thus the user may grasp the handles 13 and 14 with the right and left hands, respectively, and through rotation of the sleeve 12, may locate the clamp 16 in an out-of-the-way position as shown in Fig. 1, to thereby expose the tines 15 for insertion into the fire bed. With the tool thus grasped, the spacing of the handles 13 and 14 facilitates proper manipulation and insures proper and efficient application of forces to the tongs in the clinker loosening as well as in the clinker clamping and removing operations.

The tool is used in the position or relation shown in Fig. 1 to loosen the clinker and move the clinker into an elevated position on or in the fire bed, thereby to enable opposite sides of the clinker to be engaged readily by the tongs, and the sleeve 12 is then rotated to the position shown in Fig. 2, to thereby locate the clamping member 16 in position for clamping the clinker against the tines 15. During such rotation it will be observed that the sleeve 12 is withdrawn toward or to its most outward position which is limited by engagement of the outer end with the handle 13, such endwise withdrawal of the sleeve 12 serving to shift the clamping member 16, and particularly the cross bar 25 thereof to a relation wherein the bar 25 will clear the adjacent side face of the clinker C. In other words, such withdrawal of the sleeve 12 opens the tongs so as to present their maximum throat opening.

The sleeve 12 is then forced forwardly with relation to the rod 11, and the clinker C is

thereby clamped against the end portions 21 of the tines 15. While this clamping engagement of the clinker is maintained the entire clinker tong structure and the clinker clamped thereby are rotated generally about the axis of the handle shaft 10, thereby to position the clinker over and upon the spaced intermediate portions 19 of the tines 15. After the clinker has been thus positioned, the clamping force exerted thereon may be released or materially reduced, for as clearly shown in Figs. 4 and 6, the clinker is then cradled upon the spaced tines 15 in much the same manner as such a clinker would be supported on a shovel or fork. There is, however, an additional supporting and positioning action exerted at this time by the end portions 21 of the tines, for it will be seen that during such time as the handle shaft 10 slopes downwardly into the furnace, the end portions 21 of the tines serve to maintain the clinker C on the intermediate portions 19 of the tines.

With the clinker C thus supported upon the tines 15 the tool, and the clinker carried thereby, may be withdrawn from the furnace and the clinker may be discharged to the ash receiver simply by rotation of the clinker tong to the position shown in Fig. 5. Since the clinker need not be clamped during the removing operation, there is no danger that the clinker may be split and dropped. Moreover, the spacing of the handles 13 and 14 enables the tool to be manipulated easily and accurately, thereby simplifying the removal of the clinkers.

From the foregoing it will be evident that the present invention enables clinkers to be loosened and removed from the fire bed of a furnace with the minimum of effort. It will also be that breaking of the clinkers during the removing operation is substantially eliminated, thereby obviating one of the most objectionable features of clinker removing operations.

Hence, while I have illustrated and described preferred embodiments of my invention, it is to be understood that these are capable of variation and modification and I therefore do not wish to be limited to the precise details set forth, but desire to avail myself of such changes and alterations as fall within the purview of the following claims:

I claim:

1. In clinker tongs, an elongated handle shaft adapted to be grasped at one end by a user and having a pair of spaced tines extending from said other end at a slight angle to the longitudinal axis of said handle and then bent to extend at their end portions at an angle of approximately ninety degrees to said axis whereby said end portions of said tines may be used to loosen a clinker from a fire bed when said handle shaft is extended inwardly and downwardly through a furnace door and into the fire box of such a furnace, clamping means on said handle shaft shiftable to an unclamped relation wherein said clamping means will clear the fire bed during such a clinker loosening operation, and means for operating said clamping means to clamp a clinker against the side surfaces of said end portions and whereby said tongs and the clinker may be rotated about said axis of said handle to rest the clinker on the spaced intermediate portions of said tines.

2. In clinker tongs, an elongated member having a pair of tines at one end thereof extending in spaced relation to each other for a substantial distance at a gradually increasing an-

gle with respect to the longitudinal axis of said member and terminating in substantially parallel end portions extending substantially perpendicular to said axis, a clamp member mounted on said elongated member for shifting movement from an inactive position on the side of said elongated member opposite from the side upon which said parallel end portions of said tines are disposed and into opposed clamping relation with respect to said end portions of said tines and movable through a clamping movement in a direction toward and substantially perpendicular to the direction of extent of said end portions of said tines, and means on said elongated member adjacent to the other end thereof for manipulating said tines and for shifting said clamping member relative to said tines and whereby said tongs and a clinker clamped between said tines and said clamp member may be rotated about the axis of said elongated member to rest the clinker on said tines.

3. In clinker tongs, an elongated handle shaft adapted to be grasped at one end by a user and having a pair of spaced tines extending from said other end at a slight angle to the longitudinal axis of said handle shaft and then bent to extend at their end portions at an angle of approximately ninety degrees to said axis whereby said end portions of said tines may be used to loosen a clinker from a fire bed, clamping means on said handle shaft shiftable substantially about the axis of said handle shaft to an unclamped relation wherein said clamping means will clear the fire bed during such a clinker loosening operation, and means for operating said clamping means to clamp a clinker against the side surfaces of said end portions whereby the clinker may be shifted to a point above said axis of said handle shaft to rest and support the clinker on the spaced intermediate portions of said tines.

4. In clinker tongs, an elongated member having a pair of tines at one end thereof extending in spaced relation to each other for a substantial distance at a gradually increasing angle with respect to the longitudinal axis of said member and terminating in substantially parallel end portions extending substantially perpendicular to said axis, an operating sleeve mounted rotatably and slidably on said elongated member, a clamp member mounted on one end of said operating sleeve for shifting movement therewith through a clamping movement in a direction substantially perpendicular to the direction of extent of and into opposed clamping relation to said end portions of said tines, means on said elongated member adjacent to the other end thereof for manipulating said tines and means on the other end of said sleeve for shifting said clamping member relative to said tines.

5. Clinker tongs of the character described comprising, in combination, an elongated handle shaft structure comprising an elongated rod and an elongated sleeve mounted for sliding and rotative movement on said rod, said rod and said sleeve being adapted to be grasped at one end by a user and said rod having a pair of spaced tines extending from said other end thereof in a generally longitudinal direction with respect to the axis of said rod and then bent to extend at their end portions at an angle of approximately ninety degrees to said axis whereby said end portions of said tines may be used to loosen a clinker from a fire bed when said handle shaft is extended inwardly and downwardly through a furnace door and into the fire box of such a furnace, and

clamping means on said sleeve shiftable to an unclamped relation by rotative and sliding movement of said sleeve so that said clamping means will clear the fire bed during such a clinker loosening operation, said clamping means being operable by sliding and rotative movement of said sleeve on said rod to clamp a clinker against the side surfaces of said end portions of said tines whereby said tongs and the clinker may be rotated about said axis of said handle shaft to 10 rest the clinker on the spaced intermediate portions of said tines for convenient removal from the furnace.

6. In clinker tongs, an elongated member having a pair of tines at one end thereof extending in spaced relation to each other for a substantial distance at a gradually diverging angle with respect to the longitudinal axis of said member and terminating in substantially parallel end portions extending substantially perpendicular to said axis, a clamp member mounted on said elongated member for shifting movement into opposed clamping relation with respect to said end portions of said tines, said clamp member having a transverse clamping bar at its ends adapted to be disposed substantially perpendicular to the end portions of said tines and movable through a clamping movement in a direction toward and

substantially perpendicular to the direction of extent of said end portions of said tines, and means on said elongated member adjacent to the other end thereof for manipulating said tines and for operating said clamping member.

5. A clinker tongs of the character described comprising, in combination, an elongated member having a pair of tines at one end thereof extending in spaced relation to each other for a substantial distance and terminating in substantially parallel end portions extending substantially perpendicular to the longitudinal axis of said member, an operating sleeve mounted rotatably and slidably on said elongated member, a T-shaped clamp member mounted on one end of said operating sleeve for shifting movement therewith through a clamping movement in a direction substantially perpendicular to the direction of extent of said end portions of said tines to move the cross portion of said T-shaped clamp member into clamping relation to said end portions of said tines, operating means on said elongated member adjacent to the other end thereof for manipulating said tines, and means on the other end of said sleeve in substantially spaced relation to said operating means for shifting said clamping T-shaped member relative to said tines.

GEORGE S. PETERS.
